CLAIM

The ornamental design for an agricultural vehicle, as shown and described.

DESCRIPTION

FIG. 1 is a first side perspective view of an agricultural vehicle in accordance with the present design;

FIG. 2 is a second side perspective view of the agricultural vehicle;

FIG. 3 is a first side view of the agricultural vehicle;

FIG. 4 is a second side view of the agricultural vehicle;

FIG. 5 is a front view of the agricultural vehicle;

FIG. 6 is a rear view of the agricultural vehicle; and,

FIG. 7 is a top view of the agricultural vehicle.

The broken lines in the drawings represent portions of the agricultural vehicle that form no part of the claimed design. In addition, any shading forms no part of the claimed design and is provided to illustrate contour only and is not an indication of texture, gloss, and the like.

1 Claim, 7 Drawing Sheets
